UNITED STATES PATENT OFFICE

WILLIAM R. MORE, OF SPOKANE, WASHINGTON

CALENDAR

Application filed January 27, 1930. Serial No. 423,607.

My present invention relates to improvements in calendars of the double reel, endless web type in which are embodied webs bearing the numbers of the days of the months; the names of the months of the year; and the names of the days of the week and the single current year is also designated. A clutch take-up device is used in connection with the two webs for the days of the week and the numbers or dates of the month, and an independent take up device is utilized for changing the web bearing the names of the months.

The calendar of my invention is designed especially for use upon a desk, and is herein shown as part of a desk-set that also includes a pair of desk pens, but it will be understood that the calendar may be used separately, or combined with other similar desk furniture, stationery, &c.

The invention consists in certain novel combinations and arrangements of parts as will hereinafter be more fully set forth and claimed. In the accompanying drawings I have shown one complete example of the physical embodiment of my invention wherein the parts are combined and arranged according to the best mode I have thus far devised for the practical application of the principles of my invention.

Figure 1 is a face view of the calendar. Figure 2 is a view showing a portion of the casing in section and disclosing the endless web bearing the names of the months of the year, together with the take-up device.

Figure 3 is a detail sectional view of the take-up devices for changing the exhibited characters of the day and date webs.

Figure 4 is a perspective detail view of a portion of the web bearing the designations of the days of the week.

Figure 5 is a vertical sectional view of the housing or casing as at line 5—5 of Figure 6.

Figure 6 is a vertical sectional view of the casing, as at line 6—6 of Figure 5.

Figure 7 is a detail perspective view of the take-up clutch device, jointly, for the webs bearing the designations of the months of the year and the dates of the months.

Figure 8 is a perspective view showing the rollers that guide the webs which designate

the days of the week and the dates of the month.

Figure 9 is a perspective view showing the re-setting device for one of the webs.

In the preferred form of my invention I have shown the calendar supported upon a base plate or block 1, with desk-pens P and holders H at opposite sides of the calendar casing 2, in which casing the operating parts of the calendar are enclosed.

In Figure 1, windows or openings are shown in the front of the casing, the window 3 disclosing the name of the month, window 4 disclosing the day of the week, and window 5 disclosing the date of the month. The numbers for a single year are disclosed at 6, and this disclosure may be a printed slip set in a pocket in the front of the calendar casing which is included in the group of designations for the calendar.

A knurled turning-knob 7 is located at the right side of the casing as a take-up and setting device for the web of the months; the knob 8 is the re-setting knob for the web bearing the days of the week; and the knob 9 located at the right side of the casing, opposite the knob 8 is used for re-setting the web bearing the dates of the month. The webs for the days of the week and the dates of the month are provided with separate re-setting devices, and they are jointly provided with single-operated, duplex, take-up clutch, as will be described.

The endless web 10 bearing the names of the months, extends transversely of the casing and is supported on spaced, vertically arranged rollers 11 and 12, journaled in brackets 13 secured to the side walls of the casing, and the web along its upper edge is provided with a series of spaced holes or perforations 14. One of the rollers, as 12, is fashioned with a sprocket wheel 15 at its upper end and the teeth of the sprocket engage in the holes of the web. The roller 12 and its sprocket are turned through rotation of the knob 7, and a bevel-gear couple 16, the latter inside the casing, while the knob of course is exterior of the casing. By turning the knob the web is moved one step, each month, 100

to change the designation appearing through the window or opening 3.

The re-setting knobs 8 and 9 at the top of the casing are supported, on a transversely extending rod 17 which passes through the casing, and a pair of tubular shafts 18 and 19 are rotatable on the rod. The knobs 8 and 9 are secured to the respective shafts 18 and 19, and to each of these shafts is secured a roller, as 20 and 21. Each roller is fashioned with a sprocket wheel, as 22 and 23, and at their inner, adjoining ends the rollers are formed as bushings 24 with a plurality of faces. With these polygonal faces of the bushings a pair of spring detents co-act to provide resilient brakes or detainers for holding the rollers against movement, except when turned by the use of their knobs. The detents are spring blades that are anchored as at 26 to the back wall of the casing.

The web bearing the days of the week is designated 27, and this web, which passes around the roller 20 is fashioned with a series of holes 28 along its inner edge to co-act with the sprocket wheel 22 of the roller 20. At its lower end, the endless web 27 passes around an idler or guide roller 29, which is journaled on the cross rod 30, fixed at its ends 31 in the opposite side walls of the casing.

A complementary roller 32 is also journaled to turn on the rod 30 and the web 33 for the dates of the month passes around this guide roller. The endless web 33 passes around the roller 21 and the web is fashioned with a series of holes 34 along its edge to co-act with the sprocket wheel 23 of the roller 21.

A friction brake is employed for the shaft 30 to offer a slight resistance to its movement, for the purpose of stabilizing the turning movement of the shaft 30. This brake comprises a spring blade 35 that frictionally engages against the shaft 30 at its free end, the fixed end of the spring being secured at 36 to one of the walls of the casing, and a tension pin 37 is used to hold the free end of the spring on the shaft.

The webs 27 and 33 are separably set and reset by turning their knobs 8 and 9, but they are jointly moved, daily, to change the day of the week and the date of the month, by depressing a knob 38 at the front of the casing.

The knob is carried at the free end of a take-up lever or clutch lever 39 within the casing and pivoted at 40 on the inner face of the back wall of the casing. A spring 41 connected to the lever and anchored at 42 on the casing holds the lever up and returns it to elevated position after it has been depressed to move the webs 27 and 33, one stroke of the lever being required to move the webs the distance between adjoining holes in the respective webs.

The lever passes through a slot 43 in the front of the casing, and within the casing a slide plate 44 is carried on the lever, said plate being vertically movable or slidable in the guide grooves 45 fixed at the inner side 70 of the front plate of the casing, the plate being slotted at 46 to permit the required relative movement between the plate and the lever when the latter moves on its pivot and the former slides vertically.

At the top of the slide plate an arm 47 is hinged at 48, and this arm is fashioned with two rigid pawls 49 and 50 at opposite sides of the arm and aligned with the path of movement of the slotted edges of the webs 37 and 33. The arm 47 is fashioned with a lug 51 and a coiled spring 52 connects the lug with the lever 39. The spring normally holds the arm 47 with the pawls retracted or away from the path of movement of the adjoining inner edges of the webs 37 and 33. But when the knob 38 is depressed, the downward perpendicular movement of the slide plate causes the arm 47 to swing forward on its hinge 48. The swinging movement of the arm brings the two pawls into complementary holes 28 and 34, and the continued depression of the knob causes the pawls, as they are engaged in the holes, to wind the webs the distance between adjoining holes, thus changing the day of the week and the date of the month. When the depressed knob is released, spring 41 returns the lever to normal position, and as the slide plate 44 ascends, arm 47 is released so that spring 52 may withdraw the pawls from the holes 28 and 34.

The knob 38 is depressed daily; the knob 7 is turned monthly, and of course the two knobs 8 and 9 are set monthly to coordinate the days of the week with the dates of the particular month.

Having thus fully described my invention, what I claim as new and desire to secure by Letters Patent is:—

1. The combination in a calendar of the endless web and double reel type with a plurality of webs and setting devices for said webs, of a take-up device comprising a single lever, and duplex means actuated by the lever 115 for co-action in moving the webs.

2. The combination in a calendar of the endless web and double reel type, with a plurality of webs having spaced holes therein and setting devices for said webs, of a pivoted take-up lever, a guide device on the lever, and a pair of pawls carried by said device for co-action with the holes in the webs.

3. The combination in a calendar of the 125 endless web and double reel type, with a plurality of webs having spaced holes in adjoining edges, and setting devices for said webs, of a pivoted take-up lever and a return spring therefor, a relatively movable slide 130

plate on the lever and a guide for the plate,
an arm hinged on the plate and duplex pawls
on the arm for co-action with the two series
of holes, and a spring connecting the arm
5 with the lever.

In testimony whereof I affix my signature.

WILLIAM R. MORE.
